GEORGE W. PATTERSON, OF ASBURY PARK, NEW JERSEY.

TROLLEY-POLE.

No. 826,319.

Specification of Letters Patent.

Patented July 17, 1906.

Application filed August 11, 1905. Serial No. 273,735.

To all whom it may concern:

Be it known that I, PEMBERTON DUDLEY, a citizen of the United States, and a resident of Asbury Park, in the county of Monmouth and State of New Jersey, have invented a new and Improved Trolley-Pole, of which the following is a full, clear, and exact description.

The purpose of the invention is to provide a ball-and-socket connection between the fork for the trolley wheel and the pole and a laterally-curved guide and support for the fork, which construction is simple, economic, and effective and allows the trolley-wheel to accurately follow the wire even when the wire is not exactly overhead and also to follow the wire upon all manner of curves, said construction also insuring the wheel being straight upon the wire regardless of the angle of the pole.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a front elevation of the upper end of a trolley-pole, the fork-holder, and fork, showing the latter in two positions. Fig. 2 is a vertical section taken substantially on the line 2 2 of Fig. 1; and Fig. 3 is a sectional plan view of the device, the section being taken substantially on the line 3 3 of Fig. 2.

A represents the trolley-pole, and B the support connected with the trolley-pole and adapted as a guide, as well as a support, for the fork C. The support B is hollow and in general contour is similar in outline to the outline of an inverted triangle, the side edges extending outward and upward in opposite directions from its contracted end, and the upper and wider end is open and is rendered more or less convex, while at the lower and contracted end of the said combined guide and support B a circular socket 10 is produced, as is shown in Fig. 2.

The combined guide and support B is made as light as possible consistent with

strength and is constructed in two sections 11 and 12, the dividing line being centrally and longitudinally located. The section 11 is integral with the pole A; but the section 12 has a hinged connection 14 with the pole, as is shown in Fig. 1, and the two sections are held together by forming lugs 13 and 13^a at the central portions of the side faces A of the said sections and passing bolts 14^a through said lugs.

In addition to the peculiar fan or angular formation of the combined holder and guide B the said holder or guide is laterally curved, its one face 15 being concaved and the opposing face 16 convex, as is shown best in Fig. 3. The socket 10 is partially in one section and partially in the other section of the holder.

The trolley-wheel 17 is mounted to turn in the usual manner in the fork C, and the said fork C is provided with a downwardly-extending stem 18, substantially rectangular in cross-section. The said stem passes loosely down through the said holder B, being adapted for free lateral movement in the said holder, as the said stem terminates in a ball 19, mounted loosely in the aforesaid socket 10. It will be understood that any approved means for oiling the ball may be provided.

In order that the fork C shall be normally centrally located with respect to the holder, as is shown by full lines in Fig. 1, springs 20 bear against opposite curved sides of the shank or stem 18 of the fork, which springs are located within the holder B and are secured to the side walls of the said holder near its lower end by bolts 21 or their equivalents.

When a trolley-pole has the above-described improvements applied, the trolley-wheel is bound to follow the wire even when the wire is not exactly overhead and will positively follow the wire under all manner of curves. Even if the pole is at an angle of thirty degrees to the car the curvature in the fork-holder will permit the wheel to still keep straight on the wire and not cant in direction of the pole.

Having thus described my invention, I claim as new and desire to secure by Letters Patent—

1. A trolley-pole, a trolley-fork having a

- ball-and-socket connection therewith, and a lateral guide for the fork located above its ball-and-socket connection.
2. A trolley-pole, a trolley-fork having a ball-and-socket connection with the pole, and a holder in which the fork has guided movement, said holder being laterally curved.
3. A trolley-pole, a substantially triangularly-shaped hollow holder having its contracted end connected with the pole, being open at the top and provided with a circular socket at its bottom portion, one side face of the said holder being concaved and the other convexed, a trolley-wheel fork, a shank extending from the fork into the said holder, having lateral movement therein, and a ball at the lower end of the shank fitted in the socket at the bottom of said holder.
4. A trolley-pole, a substantially triangularly-shaped hollow holder having its contracted end connected with the pole, being open at the top and provided with a circular socket at its bottom portion, one side face of said holder being concaved and the other convexed, a trolley-wheel fork, a shank extending from the fork into the said holder, having lateral movement therein, and a ball at the lower end of the shank, fitted in the socket at the bottom of the said holder, springs located within the said holder, being secured at their lower ends and having bearing at their upper ends against opposite sides of the shank of the said trolley-wheel fork.
5. The combination with a trolley-pole 35 and a substantially triangularly - shaped holder having its contracted end connected with the pole and its upper and wider end open, a socket being formed at the lower or contracted end of the said holder, the said holder 40 being constructed in two sections, one section integral with the pole and the other section having hinged connection with said pole, one side face of the said holder being concaved and the other face convexed, and 45 means for securing the sections of the holder together, of a trolley-wheel fork, a shank extending from the said fork into the said holder, a ball at the lower end of the said shank, which is fitted in the said socket in 50 the holder, and springs located within the holder, secured at their bottom ends, their upper ends being free and in engagement with opposite sides of the shank of the said trolley-wheel fork.

In testimony whereof I have signed my name to this specification in the presence of two subscribing witnesses.

PEMBERTON DUDLEY.
